CLAIM

The ornamental design for a ventilated, quick access inspection plate for riding trowels, as shown.

DESCRIPTION

FIG. 1 is a front isometric view of my ventilated, quick access inspection plate for riding trowels;

FIG. 2 is a rear isometric view thereof;

FIG. 3 is a front elevational view thereof;

FIG. 4 is a side elevational view taken from the right of FIG. 3;

FIG. 5 is a top plan view thereof; and,

FIG. 6 is a bottom plan view thereof; and,

FIG. 7 is a rear elevational view thereof.
